UNITED STATES PATENT OFFICE.

ERNEST G. DANN, OF CHICAGO, ILLINOIS.

ERASER.

No. 817,888.

Specification of Letters Patent. Patented April 17, 1906.

Application filed November 24, 1902. Serial No. 132,693.

To all whom it may concern:

Be it known that I, ERNEST G. DANN, a citizen of the United States, residing at Chicago, in the county of Cook and State of Illinois, have invented certain new and useful Improvements in Erasers, of which the following is a specification.

The object of my invention is to provide a noiseless eraser made entirely of non-resonant material, so constructed as to afford a maximum of wearing and dust-removing qualities and so constructed that it may be manufactured rapidly and cheaply.

Another object of my invention is to provide a method of making this eraser which shall cheapen its manufacture and which shall utilize the spreading qualities of the erasing strips to form an elastic and sufficiently firm erasing-surface.

The foregoing and such other objects as may hereinafter appear are attained by the devices and the method illustrated in the accompanying drawings, in which—

Figures 1 and 2 represent successive steps in the practice of my method in the manufacture of my improved eraser. Fig. 3 indicates a perspective view of a complete eraser in modified form. Fig. 4 is a cross-section of a completed eraser. Figs. 5 and 6 are details of a modified construction, and Fig. 7 is a cross-sectional view of Fig. 3 on the line 7-7 looking in the direction indicated by the arrows.

Like letters of reference indicate the same parts in the several figures of the drawings.

Referring by letter to the accompanying drawings, A represents a strip of heavy felt or other suitable non-resonant material, which forms the back or handle part of my eraser.

B, C, D represent strips of felt or other suitable non-resonant material possessing some degree of elasticity. These strips form the rubbing or erasing surface of the eraser.

In constructing my eraser I take the strip A, from which I wish to form the back of my eraser, and lay thereon a flat strip of felt or the like. The strip B is then sewed or otherwise suitably attached while flat to the back A in the manner shown in Fig. 1. I then bend the strip B out of the way and lay the strip C flat upon the back A and sew or otherwise suitably secure the strip C to the back A on a line near the edge of the back A opposite to the edge to which the strip B has been attached. I then take flat strips D, which

are approximately twice as wide as the strips B and C, and bending the strips B and C outwardly as far as possible I attach the strips D to the back A along their central longitudinal line and along a line on the back A which is parallel with the line of attachment of the strips B and C, respectively, and is separated therefrom by a space the width of which is approximately equal to twice the thickness 65 of the felt strips B, C, and D.

Assuming that the rubbing-surface is to be formed, as shown in the drawings, of five strips, I complete my eraser by pressing the previously-attached strips outwardly in opposite directions away from the center longitudinal line of the back A and then sew or otherwise suitably secure a fifth flat strip along its center longitudinal line to the back A upon a line which is approximately the 75 center longitudinal line thereof.

It is obvious that by constructing an eraser in the manner described I produce an eraser which is free from any substance which can either injure the blackboard or be capable of 80 making any noticeable sound, and by forming the rubbing portion of flat strips which are attached to the back of the eraser and adjoining each other the tendency of each strip to flatten out is opposed by the flattening 85 tendency of the immediately-adjacent strip, with the result that the point of equilibrium between these opposing forces is reached only when the strips are in a position substantially at right angles to the back, and so I produce 90 an eraser in which the rubbing or erasing surface will not be readily flattened out or rendered inefficient when in use and in which under ordinary rubbing or erasing pressure the spaces between the different folds of felt 95 forming the ways or channels for the reception of the chalk-dust will be continually opened and closed in a manner which proves most efficient in removing chalk-dust from the board, and because of the material of 100 which this eraser is composed and the manner in which it is assembled the effective life of this eraser is prolonged until the strips forming the rubbing-surface are substantially worn away, the eraser meanwhile not only 105 being effective for erasing chalk-marks from a blackboard, but also remaining efficient as a dust-gatherer.

In Figs. 5, 6, and 7 I have shown a modification in the construction of my eraser. In 110 this modification in place of the strips D, I use strips d, which preferably at about their

mid-width are longitudinally cut part way through, as shown in Fig. 5. This facilitates the securing of the erasing-strips to the back-piece or handle, still leaving sufficient of the material to afford a hold for the stitches, and, furthermore, affords substantially square shoulders which rest against the back-piece, and in conjunction with the tightly-drawn stitches serve to hold the erasing-strips substantially vertical to the handle and allow of the adjacent erasing-strips being fitted snugly together, as shown in Fig. 7, whereby the strips afford each other a better support and a firmer and more compact eraser is made.

By my method these erasers may be made cheaply and rapidly, may be made of any desired width, and may be made in long strips which when made up can be subsequently cut into the proper lengths for the finished erasers.

Various modifications as to the materials used and the means of attachment between the back and the rubbing-surfaces will readily occur, which, however, do not depart from the spirit of my invention.

While I have shown and described my invention as a blackboard-eraser, it is obviously adapted for many similar uses—such as a slate-cleaner, a furniture-polisher, shoe-polisher, and the like—and is adapted for various uses where the absence of any material in its composition which would mar or scratch the article to which it is applied will especially commend it, and all such adaptations and uses of my invention are contemplated hereby.

I claim—

1. An eraser, comprising a non-resonant back-piece, and a plurality of strips of erasing fabric, each strip being folded upon itself and being stitched to the back-piece along the folded edge, and each folded strip being arranged closely adjacent to the next folded strip, substantially as described.

2. An eraser, comprising a non-resonant back-piece and a plurality of strips of resilient erasing material, each strip being folded upon itself and stitched to the back-piece along its folded edge, said folded strips being arranged closely adjacent to one another, so as to provide a mutually elastic support, substantially as described.

3. An eraser, comprising a non-resonant back-piece and a plurality of strips of felt, each strip of felt being folded upon itself and being tightly stitched to the back-piece along

its folded edge, said folded strips of felt being arranged closely adjacent to each other, so as to provide a mutual, resilient support, substantially as described.

4. An eraser, comprising a back-piece and a plurality of felt strips, each strip being folded upon itself and also cut part way through along the outer edge of such fold and being firmly secured to said back-piece along said folded and cut edge, said strips being arranged closely adjacent to each other to form a resilient erasing and dust-collecting face, substantially as described.

5. An eraser, comprising a non-resonant back-piece and a plurality of non-resonant erasing-strips, stitched to said back-piece and arranged closely adjacent to each other to afford a mutual support and to provide a resilient erasing and dust-collecting face, substantially as described.

6. An eraser, comprising the combination with a back-piece of non-resonant material, of strips of erasing fabric folded upon themselves and cut part way through along their folded edges, said strips being arranged closely adjacent to each other, the faces formed by said cuts being arranged against one face of the back-piece, said strips being sewed to said back-piece along the lines of said cuts.

7. An eraser, comprising a back-piece of non-resonant material, provided with folded strips of erasing fabric, attached at their folded edges to one face of said back-piece, each strip being arranged substantially parallel with every other strip and being arranged immediately adjacent to the next strip, so that said strips shall directly support each other in a position substantially at right angles to said back-piece, substantially as described.

8. An eraser, made wholly of non-resonant material and comprising a non-resonant back-piece and a plurality of non-resonant strips of resilient erasing fabric, each strip being folded upon itself and being tightly stitched along said folded edge to said non-resonant back-piece, said strips being arranged closely adjacent to and parallel with each other, so as to afford a mutual support, said strips, so arranged, projecting at a right angle to said back-piece and constituting a resilient dust-collecting and erasing surface.

ERNEST G. DANN.
